UNITED STATES PATENT OFFICE.

MOSES NICHOLLS, OF OTTUMWA, IOWA, ASSIGNOR OF THREE-FOURTHS
TO J. D. GRAY, OF OTTUMWA, IOWA.

RAFTER ATTACHMENT FOR STEEL SQUARES.

SPECIFICATION forming part of Letters Patent No. 795,160, dated July 18, 1905.

Application filed September 26, 1904. Serial No. 225,943.

To all whom it may concern:

Be it known that I, MOSES NICHOLLS, a citizen of the United States of America, and a resident of Ottumwa, Wapello county, Iowa, have invented a new and useful Rafter Attachment for Steel Squares, of which the following is a specification.

The object of this invention is to provide an attachment for use on a steel square whereby the desired length of rafters, hip-rafters, valley-rafters, and the various cuts thereof may be ascertained without computation.

My invention consists in the construction, arrangement, and combination of elements hereinafter set forth, pointed out in my claims, and illustrated by the accompanying drawings, in which—

Figure 1 is a plan illustrating the construction and use of my improved device. Fig. 2 is a cross-section on the indicated line 2 2 of Fig. 1. Fig. 3 is a cross-section on the indicated line 3 3 of Fig. 1. Figs. 2 and 3 are materially enlarged.

In the construction of the device as shown the numeral 10 designates a clip which is formed with a longitudinal slot 11, adapted to admit and slidingly engage the blade 12 of a steel square of ordinary construction. A set-screw 13 is mounted in and longitudinally of one end portion of the clip 10 and is adapted to engage the inner margin of the blade 12 and lock the clip thereto. The end of the clip 10 opposite to the set-screw 13 is curved on half of a circle of the width of the clip (dotted lines, Fig. 1) and projects beyond the margin of the square-blade the amount of its radius. The clip 10 is preferably exactly one inch in width. A stud 14 is formed on and projects from the face of the clip near its outer end, and the center of said stud is coincident with the axis of the adjacent rounded end of the clip. A bar 15 is provided and is rounded on a half-circle at one end and pivoted by a central aperture in said rounded end engaging and embracing the stud 14. A clip 16 is formed with a longitudinal slot 17, adapted to admit and slidingly engage the tongue 18 of the square. The tongue 18 is ordinarily made of one of two widths—namely, one and one-half inch or one

and one-quarter inch—and the slot in the clip 16 is made to receive the wider tongue. In the event that the clip 16 is employed on a narrower tongue a plate or strip 19 is mounted between the inner end of the slot 17 and the inner margin of the tongue. A set-screw 20 is mounted in and longitudinally of the inner end portion of the clip 16 and engages the inner margin of the tongue 18 or the strip 19 and locks the clip to the tongue. The bar 15 preferably is formed with a longitudinal slot 21, and a bolt 22 is seated in the clip 16 and extends through said slot. A washer 23 is mounted on the bolt 22 and is formed with an index or pointer 24, projecting from its rim, and a tightening-nut 25 is screwed on the outer end portion of the bolt and impinges the washer and binds the bar 15 to the clip 16.

The face of the square is graduated on its outer margin to inches and twelfths of inches, and the bar 15 is graduated on its outer margin to inches and twenty-fourths of inches.

In use to find the length of a common rafter the clip 10 is locked on the blade, with the forward margin a one-half inch in advance of the run indicated on the blade 12, thus bringing the center of the stud 14 and the axis of oscillation of the bar 15 over the indication of the run. The clip 16 is moved along the tongue 18 until the pointer 24 indicates the rise in the blade and is locked by tightening the set-screw 20 and the nut 25. The point on the graduation of the bar 15 indicated by the pointer 24 will show the length of the common rafter, and by placing the bar 15 against one side of the stick being framed the outer margin of the blade will show the angle of the top cut, and the outer margin of the tongue will show the angle of the bottom cut, of the rafter. Taking the length of the common rafter and the run on the tongue and blade, respectively, and the bar, properly adjusted again, will indicate the length of hip or valley rafter. As adjusted to show the length of the hip or valley rafter the angles of the bar to the tongue and blade may be used as a base and a bevel-square used to determine the side cuts of the hip or valley rafter.

I claim as my invention—

1. The combination with a steel square of a clip mounted on and adjustable longitudinally of the blade thereof, the outer end portion of said clip curved on a half-circle of the width of the clip, a stud on said clip, the center of the stud coincident with the axis of the rounded outer end portion of the clip, a graduated bar pivoted on said stud, a clip mounted on and adjustable longitudinally of the tongue of the square and sliding connections between the latter clip and said bar.
2. The combination with a steel square of clips mounted adjustably on the blade and tongue thereof, a bar pivoted on the clip on the blade and formed with a longitudinal slot, a bolt mounted in the clip on the tongue and projecting through the slot of the bar, a washer on said bolt and adapted to bind the bar to said clip, said washer formed with a pointer adapted to indicate graduation-marks on the bar and tongue, and a nut on the outer end of said bolt and impinging said washer.
3. The combination with a steel square, of a clip formed with a slot to receive the blade of said square, the outer end portion of said clip rounded on a half-circle having its axis coincident with the outer margin of the square and midway of the side margin of the clip, a stud on said clip, the center of the stud coincident with the axis of the rounded outer end portion of the clip and the outer margin of the blade, a clip mounted on and adjustable longitudinally of the tongue of the square, a graduated bar pivoted at one end on the stud and formed with a longitudinal slot, and a fastening device on the second clip and extending through the slot in the bar, the fastening device provided with a pointer indicating graduating-marks on the bar.

Signed by me at Ottumwa, Iowa, this 9th day of May, 1904.

MOSES NICHOLLS.
